UNITED STATES PATENT OFFICE.

WILLIAM H. HEULINGS, JR., OF PHILADELPHIA, PENNSYLVANIA.

DESIGN FOR AN ORNAMENTAL METAL MOLDING.

47,724.

Specification for Design.

Patented Aug. 17, 1915.

Application filed March 19, 1915. Serial No. 15,632. Term of patent 7 years.

To all whom it may concern:

Be it known that I, WILLIAM H. HEULINGS, Jr., a citizen of the United States, residing at Philadelphia, in the county of Philadelphia and State of Pennsylvania, have invented a certain new, original, and ornamental Design for Ornamental Metal Moldings, of which the following is a specification, reference being had to the accompanying drawing, forming part hereof.

The figure is a perspective view of an ornamental metal molding, showing my new design.

I claim:

The ornamental design for a metal molding, as shown.

WILLIAM H. HEULINGS, JR.

Witnesses:

HENRY C. ESLING,
H. F. MCKILLIP.
